Primary Examiner — Jennifer L Rempfer*Assistant Examiner* — Danielle Nichole Bowly(74) *Attorney, Agent, or Firm* — Xsensus LLP(57) **CLAIM**

The ornamental design for a printer, as shown and described.

DESCRIPTION

FIG. 1 is a front, top, and left side perspective view of a printer;

FIG. 2 is a front, top, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front, top, and left side perspective view thereof with the monitor in an alternate position;

FIG. 10 is a front elevational view thereof with the monitor in the alternate position;

FIG. 11 is a right side elevational view thereof in the use condition with the monitor in the alternate position; and, FIG. 12 is a left side elevational view thereof in the use condition with the monitor in the alternate position.

The broken lines shown in the figures illustrate portions of the printer that are not part of the claimed design.

1 Claim, 12 Drawing Sheets(56)
